UNITED STATES PATENT OFFICE.

GEORGE P. CRAMER AND FRED B. LANGWORTHY, OF INDIAN FORD, WIS.

HARNESS-BUCKLE.

SPECIFICATION forming part of Letters Patent No. 339,528, dated April 6, 1886.

Application filed November 11, 1885. Serial No. 182,492. (No model.)

To all whom it may concern:

Be it known that we, GEORGE P. CRAMER and FRED B. LANGWORTHY, citizens of the United States, residing at Indian Ford, in the 5 county of Rock and State of Wisconsin, have invented new and useful Improvements in Harness-Buckles, of which the following is a specification.

The invention relates particularly to the 10 tug-buckles of harness.

The object of the improvement is to furnish a construction whereby the trace may not only be easily shifted without withdrawing it from the keeper-loop in the tug, but also whereby 15 a draft is obtained without direct strain upon the tongue. How these objects are effected is shown in the following description and accompanying drawings, wherein—

Figure 1 represents in side elevation portions of a trace and its tug secured by our 20 improved buckle; Fig. 2, a perspective view of the metal buckle parts as joined for fastening trace to tug, the trace and tug being shown by dotted lines; Figs. 3 and 4, details of the 25 clamp-loop piece and the bail; and Fig. 5, an elevation showing the manner of shifting the trace without taking it out of its keeper in the tug.

In these drawings, A is the trace, and B the 30 tug. C is the metallic clamp-loop, and D the metallic bail.

The clamp-loop C has its curving side bars, a, end bars, b b', and under clamping-bar, c, as shown. It receives within that part forward of its under cross-clamp bar, c, the bail 35 D, so that the bail end cross-bar e' bears upon the outer side of the trace. This bail D also has curving side bars, d, and end bars, e e', the bar e' clamping upon the trace, and the bar e being within the tug and projecting beyond 40 the side bars, d, as at f f, for a purpose to be presently described. The bail cross-bar e' is cast with the usual tongue, c', foreengaging with the trace-holes. The tug has the usual keepers, g g, and the whole is as usual, except as 45 to the above novel construction of buckle.

Now, from such a construction not only is direct draft obtained, but the trace, in being shifted, is not required to be bent at such a 50 sharp angle as would strain the stitching, and

remains within its keepers on the tug. The strain upon the tongue is almost entirely relieved by the close embrace of the two parts. This is accomplished by a compression of the metallic loop and bail upon the trace.

The usual loops for back and belly bands may be cast with the metallic loop-piece. By pressing against the end of this metallic loop and upon the projecting ends f f of the bail the tongue will come out of the hole in the 60 trace, thus leaving the trace free for adjustment without removing it from the keepers of its tug, and by pulling lengthwise on the metallic loop C, and in an opposite direction from the tug, the tongue in the bail will go to 65 the desired hole in the trace. Should the hole be small for the tongue the thumb may be used by pressing on the bail.

The bail part affords sufficient space for connecting a tug of any desirable thickness while 70 leaving space for operating buckle.

The projections f f on the bail at its connection with the tug serve to prevent its turning laterally in the tug in case the tug should become worn, and in shifting they form a bracing means for the hand in unbuckling the 75 trace.

It will be seen that the loop is in line with the strap and brings the connection of the buckle beneath the trace. Of course a buckle 80 of such construction could be used to connect any two straps.

The clamp-loop C has its bars a a flaring from the cross-bar c to the end cross-bar, b, as seen in Figs. 2 and 4, so that in pushing the 85 clamp-loop in to unbuckle the side bars, a a, of the latter will push against the curved ends of the side bars, d d, of the bail, and thus assist in lifting the tongue e' free of the trace, as seen in Fig. 5.

We claim—

1. The herein-described bail D, having the cross-bars e e', the curving side bars, d, one cross-bar, e, being within the tug, and having projections f f, the same being adapted 95 for use with a harness-buckle clamp-loop, substantially as herein described.

2. The trace-buckle herein described, consisting of the bail D, having the tongue e' and the projecting ends f f, and the clamp-loop C, 100

having the flaring side bars, *a a*, and the cross-bars *b b' c*, the curved tongue end of the bail fitting within the flaring end of the loop, so that the side bars of the latter will act upon

5 the side bars of the bail and lift it in unbuckling.

In testimony whereof we have hereunto set

our hands in the presence of two subscribing witnesses.

GEORGE P. CRAMER.
FRED B. LANGWORTHY.
